To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The floral designs within the faggotted ovals on the sleeves of the jacket and on the front and back of the collar of the dress member of the ensemble, represent quilted embroidery.

The faggotted strip extending around the back portion of the collar, terminates at the front shoulder portion of the collar.

I claim:

The ornamental design for an ensemble dress, substantially as shown, and described.
